Primary Examiner — John R Yeh

(57) **CLAIM**

The ornamental design for a device for machine washing and drying delicate articles, as shown and described.

DESCRIPTION

FIG. 1 is a front plan view of my design for a device for machine washing and drying delicate articles in a closed configuration, the rear plan view being a mirror image thereof;

FIG. 2 is a top view thereof;

FIG. 3 is a bottom view thereof;

FIG. 4 is a right side view thereof, the left side view being a mirror image thereof; and,

FIG. 5 is a perspective view in an open configuration thereof.

1 Claim, 3 Drawing Sheets
